UNITED STATES PATENT OFFICE.

MICHAEL J. SASGEN, OF CHICAGO, ILLINOIS.

DERRICK.

947,029.

Specification of Letters Patent. Patented Jan. 18, 1910.

Application filed April 5, 1909. Serial No. 487,959.

To all whom it may concern:

Be it known that I, MICHAEL J. SASGEN, a citizen of the United States, residing at Chicago, in the county of Cook and State of Illinois, have invented certain new and useful Improvements in Derricks, of which the following is a specification.

This derrick is particularly intended for light service in hoisting building material or the like, and is intended to be easily adjustable to different positions on a building, being so constructed that it can be located at the extreme edge or corner of a roof or floor and can there be rigidly secured to handle the intended loads. The derrick is intended to swing in a complete circle, which gives it a wide radius of action, which is particularly desirable in derricks of this class.

The invention relates particularly to the derrick structure as a whole, including the means provided for mounting and anchoring the derrick; to the brake which acts upon the cable drum during the descent of the block; and to the location and arrangement of these various devices within convenient reach of the operator.

Further objects will appear from a detailed description of the invention, which consists in the features of construction and combination of parts hereinafter described and claimed.

In the drawings, Figure 1 is a side elevation of the derrick; Fig. 2 a top or plan view thereof; Fig. 3 a cross sectional view through the post, showing the drum in elevation and the band brake locked; Fig. 4 a similar view, showing the band brake unlocked and the boom swung to a different position; Fig. 5 a side elevation of the drum and associated parts; Fig. 6 a top or plan view of the drum and hangers; Fig. 7 a sectional detail, showing the band brake and collar therefor; and Fig. 8 a detail, showing the clamp for the ends of the cable.

The derrick, as a whole, is mounted upon a base comprising a pair of sills 9 and 10, set at right angles to one another and rigidly secured together. At the angle of the base is located a mast 11 which is suitably held braced by means of diagonally extending braces 12. About half way up the mast is located a grooved collar 13 provided, at suitable intervals, with ears or lugs 14 which, as shown, are four in number and are bolted to the flat sides of the mast which, in the form shown, is octagonal in shape. The

grooved collar furnishes a bearing for a swinging bracket frame 15 comprising a head having clamping arms 16 which encircle the grooved collar and terminate, at their rear ends, in a pair of ears 17, the construction being that of a split ring which is adapted to be clamped onto the collar when it is desired to lock the bracket frame against revolution. The ears 17 have entered therethrough a bolt 18, to the projecting end of which is pivoted a bifurcated handle 19. The pivot pin 20 is entered through the sides of the handle at such a point as to give an eccentric or cam action thereto, such that when the handle is thrown into the position shown in Fig. 3 the ends of the handle will act against the adjacent ear 17 and serve to draw on the bolt 18 and lock the clamping arms 16 against the grooved collar. The bracket frame 15 is further provided on its forward side with forwardly projecting arms 21, provided at their outer ends with hangers 22, which furnish a bearing for a shaft 23 which carries a drum 24 between the hangers and also serves, on one of its outer ends, to mount a brake wheel 25, outside of which is located a ratchet wheel 26. The brake wheel coacts with the brake shoe 25^a on the end of a lever 26^a, which is pivoted in its center to the bracket frame by means of a pivot rod 27, which rod is entered through the lower end of a diagonally disposed boom 28. The brake lever terminates in a handle 29, in close proximity to the bifurcated handle 19, so that the operator will find both of the handles within easy and convenient reach. The ratchet wheel 26 coöperates with a dog 30, which is pivoted to the adjacent collar. The shaft 23, at its opposite end, is provided with a supplemental handle 31 to facilitate the operation of the drum.

The boom, at its outer end, is connected with a brace beam 32 by means of plates 33, from which depends a sheave bracket 34 carrying a sheave 35, which coöperates with a block 36. A cable 37, as shown, is passed twice over the sheave, and its end 38 is looped around a hook 39 on the block 36 and back on itself, and is entered through a U shaped clamp 40 having a cross head which receives a set screw 42, which serves to compress the end of the cable against the main strand thereof and hold the loop around the hook. Obviously, the cable might be otherwise carried around the

sheave and through the block. The inner end of the brace beam 32 is provided with a tongue 43, which receives a pivot stud 44 upwardly projecting from the top of the 5 mast, which arrangement permits the boom with its brace beam to swing to any position around the mast. The boom and brace beam are further reinforced by means of a pair of vertical brace bars 45, the upper ends of 10 which are connected to the brace beam and the lower ends of which are connected to the side arms 21 of the bracket frame. The base of the derrick is adapted to be held against displacement by means of outer bolts 15 46, which are entered through the sills 9 and 10, near their outer ends, and an inner bolt 47, which is entered through one of the sills, near its point of connection with the other.

20 In use, the boom can be swung to any desired position by throwing down the bifurcated handle, as shown in Fig. 5, which unlocks the clamping arms and permits swinging of the boom. When the boom has 25 reached the desired position, it can be locked and the material hoisted by means of the drum. Thereafter, in allowing the block to descend, the brake 25^a can be thrown to retard the descent of the block and cable. The 30 arrangement is one which brings the controlling mechanism of the derrick within easy reach of the operator, and enables the derrick to be easily and readily operated to perform the light work more particularly intended. The method of supporting and 35 holding the derrick is one which permits it to be located at the extreme edge of a floor or roof and held in position by the bolts 46 and 47 without additional means of support, 40 which is highly desirable in permitting the derrick to be used in widely different conditions.

What I regard as new and desire to secure by Letters Patent is:

- 45 1. A derrick, comprising a mast, a boom outwardly projecting from the mast, a mounting for the boom adapted to permit the boom to be swung completely around the mast, and means fixedly attached to the 50 boom for clamping the boom to the mast and preventing revolution, substantially as described.
- 55 2. A derrick comprising a mast, a boom outwardly projecting from the mast, a mounting for the boom adapted to permit the boom to be swung around the mast, the 55 said mounting being in the form of a split ring, and means for clamping the mounting

to the mast to prevent revolution of the boom, substantially as described. 60

3. A derrick, comprising a mast, a boom outwardly projecting from the mast, a mounting for the boom adapted to permit the boom to be swung around the mast, the 65 said mounting being in the form of a split ring, a bolt for drawing together the ends of the split mounting, and a handle eccentrically pivoted to the bolt and adapted to move the bolt to a position to draw together the split mounting and lock the boom 70 against revolution, substantially as described.

4. A derrick, comprising a mast, a boom outwardly projecting from the mast, a mounting for the boom adapted to permit 75 the boom to be swung around the mast, means for locking the boom against revolution, a drum connected with the boom, and a brake adapted to retard the rotation of the drum, said brake being operable from 80 the position adjacent to the means for locking the boom against revolution, substantially as described.

5. A derrick, comprising a mast, a boom outwardly projecting from the mast, a 85 mounting for the boom adapted to permit the boom to be swung around the mast, the said mounting being in the form of a split ring, means for clamping the mounting to the mast to prevent revolution of the boom, 90 a drum connected with the boom, and a brake adapted to retard the rotation of the drum, said brake being operable from the position adjacent to the means for locking the boom against revolution, substantially 95 as described.

6. A derrick, comprising a mast, a boom outwardly projecting from the mast, a mounting for the boom adapted to permit the boom to be swung around the mast, the 100 said mounting being in the form of a split ring, a bolt for drawing together the ends of the split mounting, a handle eccentrically pivoted to the bolt and adapted to move the bolt to a position to draw together the split 105 mounting and lock the boom against revolution, a drum connected with the boom, and a brake adapted to retard the rotation of the drum, said brake being operable from the position adjacent to the means for locking 110 the boom against revolution, substantially as described.
